BOARD-EDGING MACHINE.

No. 877,124.

Specification of Letters Patent.

Patented Jan. 21, 1908.

Application filed June 15, 1907. Serial No. 379,272.

To all whom it may concern:

Be it known that we, LA FAYETTE G. ROBINSON and LOUIS J. HANHART, citizens of the United States, residing, respectively, 5 at Newport, in the county of Campbell and State of Kentucky, and at Cincinnati, in the county of Hamilton and State of Ohio, have jointly invented certain new and useful Improvements in Board-Edging Machines, of 10 which the following is a specification.

It is the object of our invention to provide a new and improved board edging machine, capable of providing a board with a true straight edge irrespective of previous irregularities, curves, or other unevenness or 15 imperfections in the edge of the board when in the rough, so as to permit the board to have a proper glue joint provided at its edge or to have this straight edge provided for 20 other purposes. One of the objects of providing this straight edge is to give the board an edge which may be fed against a side gage in manner so that subsequent sawing operations may be performed upon the 25 board with the assurance that these subsequent operations shall be in parallel lines so as to cut the board into longitudinal strips having parallel edges, each of the succeeding 30 edges on the board after the previous strips are cut off of the same forming the guiding edge for the succeeding cut, the line of the original edge provided by our improved device however determining the line of each 35 succeeding edge, it being understood that the board must first be provided with a straight edge before it is capable of being properly guided against a side gage for performing a straight cut lengthwise of the board. In our improved device we accomplish this by supporting the board, while 40 being so edged, preferably solely and longitudinally upon an endless bed or supporting chain, forming an endless supplemental supporting table, guided in a straight line of 45 travel, said supplemental table protruding from the upper surface of the normal table for raising the board relatively to the normal table while the same is being edged. In our improved device we provide a flat-top normal table, whereon ordinary sawing operations 50 may be performed, and whereon the board may be handled, and we embed the said endless bed or supplemental supporting table in this normal table, and we further

provide means whereby the relative height 55 between the top surface of the normal table and the top surface of the endless supplemental supporting table may be relatively adjusted to height, so as to cause the endless bed or supplemental supporting table to protrude from the upper surface of the normal table for raising the board relatively to the normal table while the edging operation is being performed, and for also permitting the upper surface of the endless bed or supplemental 60 supporting table to be on a level with or slightly below the upper surface of the normal table when the machine is being used for ordinary sawing operations, for instance, scroll-sawing purposes. 70

We also provide a pressure device above the endless supplemental supporting table for causing the board to be pressed upon the latter for causing the board to follow truly the line of travel of the endless supplemental 75 supporting table.

After the board has been provided with its straight edge, it may be readily guided in straight lines against an ordinary side gage. The subsequent sawing operations upon the 80 board, being so guided, are caused to follow the true straight line of the original straight edge provided in our improved device.

The invention will be readily understood from the following description and claims, 85 and from the drawings, in which latter:

Figure 1 represents a perspective view of our improved device. Fig. 2 is a front elevation of the same, partly broken away. Fig. 3 is a plan view of the same. Fig. 4 is a rear elevation of the driving mechanism for the feeding means. Fig. 5 is a detail of the feeding means shown in side elevation, with the lower wall of the table-groove shown in section on the line $x-x$ of Fig. 3. Fig. 6 is a 90 cross-section of the table-support of the endless bed or supplemental supporting table on the line $y-y$ of Fig. 5, showing a board being edged and the pressure-roll above the board for pressing the board upon the endless supplemental supporting table for causing it to travel in a true line with the said endless supplemental table; and, Fig. 7 is a plan view of a board having an uneven edge and having the parallel lines of the longitudinal saw-cuts 95 provided in our improved device indicated thereon.

A usual practice of edging boards hereto-

fore, has been to lay the board upon a so-called edging-board, which is then manually shoved upon guide-ways across the path of travel of the saw, the edging-board being then pushed back to original position for a succeeding cut, and in operation it was necessary to push the edging-board forward the full length of the board being edged, and to then return the edging-board to original position for a succeeding cut.

In our improved device, we dispense with edging boards, and perform the edging operation with an endless supplemental supporting table of the character and in the relation 15 mentioned, the said endless supplemental supporting table traveling continuously in one direction. In our improved construction also, the upper or supporting stretch of the endless supplemental supporting table may 20 be comparatively short, compared with the necessary length of edging boards heretofore used or the length of the board being edged.

We have exemplified our invention as embodied in a band-sawing machine, in which 25 1 represents the base, which supports a lower saw-wheel shaft 2 carrying a lower band-saw wheel 3 and mounted in suitable bearings 4. A column 5 projects upwardly from the base. A bracket 6 is adjustable on the column on 30 ways 7 by means of an adjusting screw 8 journaled in bearing 9 on the column and threaded into an internally threaded lug 10 on the bracket. The bracket 6 supports an upper saw-wheel bearing 11 provided with 35 suitable adjusting and straining devices. An upper saw-wheel shaft 12 is journaled in the bearing, an upper saw-wheel 13 being secured to said shaft. The saw-wheel shafts or mandrels 2 and 12 are parallel with each 40 other. A band-saw blade 14 takes about the saw-wheels and is driven from the lower saw-wheel in a suitable manner, as by a pulley 15.

The bracket 6, at its front end, is provided 45 with a slideway 16 in which a ram 17 is adjustable and has movement. At its lower end the ram 17 has bearings 18 19 in which shafts 20 21 are journaled, the shafts having feed-rolls 22 23 secured thereto. An arm 24 projects sidewardly from the forward end of 50 the bracket and has a lever 25 pivoted there to on a bolt 26.

27 is a T-bolt whose head and shank are 55 slidable in an undercut slot 28 in the ram, a link 29 being articulated to said T-bolt and to the lever 25 as by a bolt 30. The T-bolt is adapted to be clamped to the ram at suitable points along said slot by a nut 31.

The ram is provided with a rack 32 with 60 the teeth of which a pawl 33 is adapted to engage, being however normally out of engagement. The pawl is pivoted on a bolt 34 in a lug 35 of the arm 24. The lever 25 is arranged to take under an adjustable pin 36 selectively insertible into a series of apertures 37 at the outer end of the arm 24. This

construction is for the purpose of determining the normal height of the rolls, which latter are adjusted to a height above the normal table 38 corresponding to the thinnest lumber at the time being operated on, the said rolls yielding to inequalities in the lumber.

If it is desired to raise the rolls, the outer end of the lever 25 is depressed, which raises the ram, and the adjustable pin 36 is inserted into the proper aperture 37 for limiting the 75 rise of the outer end of the lever, and thereby limiting the drop of the rolls, the rolls however being permitted to rise as the outer end of the lever is not limited in its downward movement. If it is desired to raise the feed- 80 rolls to substantial extent, the outer end of the lever 25 is depressed, and the pawl 33 pushed into engagement with the rack 32, thereby supporting the ram. The nut 31 is then loosened, and the outer end of the lever 85 raised for sliding the T-bolt 27 in the slot 28 to a new position lengthwise of said slot, when the T-bolt is again clamped, the further depressing of the outer end of the lever 25 then causing further rise of the ram 90 and feed-rolls. A supplemental slide 42 is adjustable up and down on the ram on a slide-way 43 and is secured in place thereon by means of bolts 44. The supplemental slide carries an upper saw-guide 45.

There is a slot 47 in the normal table. An 95 endless bed 48 for the board, shown at a, is adapted to travel in this slot. This endless bed forms an endless supplemental supporting table and is composed of links 49 having a supporting face 50. The endless supplemental supporting table is adapted to form a loop 51, the upper stretch 52 of which travels adjacent to the upper face 53 of the normal table, and the lower stretch 54 of which forms a loop under the table. The 100 endless supplemental supporting table is adapted to travel over sprocket-wheels 55 56 respectively mounted on shafts 57 58. The shaft 57 is journaled in bearings 59 on 105 brackets 59' secured to the normal table. The shaft 58 is journaled in bearings 60 secured to the bottom of the normal table.

The endless supplemental supporting table is extended in width, and, as will be noted in 115 Fig. 6, when the machine is edging boards, the endless supplemental supporting table extends higher than the upper face 53 of the normal table so that the board, shown at a, may be supported upon said endless supplemental supporting table, thus raising the board above the upper surface of the normal table for relieving contact therewith, as contact between the board and normal table or with supporting parts other than said endless 120 supplemental supporting table will have the tendency to cause the board to swerve from its true line of travel, which is parallel with the path of travel of said endless supplemental supporting table. We prefer also to pro- 125 130

vide an adjustment for the endless table so that it may be lowered to bring its upper surface on a level with the upper surface of the normal table, or if desired so as to bring the upper surface of the endless table slightly below the level of the upper surface of the normal table, for putting the endless table out of commission as a guiding agency, in which case the endless table remains stationary so that the normal table or the combined tables may be used for ordinary purposes of a stationary table in other usual sawing operations. In this manner the machine is adapted not only for edging purposes but also for other sawing purposes. For readily permitting this adjustment I prefer to have the slot 47 take the form of a groove, the said groove being provided with an inclined bottom 61, the incline extending lengthwise of the groove. A wedge 62, having an inclined under-face 63 for mating the incline of the bottom of said groove, is inserted in said groove. The wedge is also provided with slide-ribs 64 adapted to engage the slide-grooves 65 of the links of the endless table, the said slide-ribs and slide-grooves being preferably V-shaped for definitely positioning the endless table laterally irrespective of wear between the parts.

For raising or lowering the upper stretch of the endless supplemental table, the wedge is adjusted longitudinally of the groove and for accomplishing this, we provide a screw-rod 66 threaded into the wedge at 67 and extending through an elongated aperture 68 in the lower wall of the groove or channel 47 of the normal table and having a hand-wheel 70, by means of which the wedge may be forced longitudinally and clamped to the normal table in desired position.

The endless supplemental table, which has an extended approximately flat upper supporting surface for the board, which may if desired be suitably roughened or knurled, operates within the normal table and travels closely adjacent to the hand-saw blade substantially parallel to the longitudinal axes of the band-saw wheels, the rolls thereabove having broad faces for forcing the board upon the endless supporting table over a large area of the latter for supporting the board and thereby compelling the board, irrespective of length, to travel coincident with the travel of the endless supporting table and thereby cutting the edge of the board in a true line parallel with the longitudinal axes of the band-saw wheel mandrels.

Our improved construction compels the board to follow definite lines of travel coincident with the travel of the endless feeding table for preventing either sidewise tilting of the board or swerving of the board lengthwise out of the path of travel of the traveling table, thereby supporting and guiding the board past the saw-blade in a true line ver-

tically and horizontally and also longitudinally of the board for providing the board with a straight edge.

Our improved construction dispenses with long edging tables as heretofore in common use, and permits the edging to be done by means of a band-saw blade which has a small kerf and thereby economizes in lumber. After the board has been edged, it may be sawed into lengths of desirable widths by again or repeatedly feeding the same through the machine with its edge against a gage 71 adjustable across the table and clamped in adjusted position in suitable manner, the original edging of the board by the machine insuring that all of said strips will be sawed in parallel lines.

For operating the feed-rolls we show a cross-shaft 72 journaled in a bearing 73 of the column and provided with a cone-pulley 74, over which and a cone-pulley 75 on the lower band-saw wheel shaft a suitable belt is adapted to travel for driving the cross-shaft at different speeds. The cross-shaft is provided with a worm 76 with a worm-wheel 77 mounted on a drive-shaft 78 journaled on the column connecting with the feed-roll shaft 20 by means of an extensible shaft 79 through knuckle-joints 80 81. The shaft 20 is provided with a sprocket-wheel 82 and the shaft 21 with a sprocket-wheel 83, over which sprocket-wheels a sprocket-chain 84 travels.

We prefer also to provide a power drive for the endless supplemental table, although the said endless table may be permitted to run idle and still perform its guiding functions, or the traveling table may be driven and the pressure-rolls above run idle. For driving the endless supplemental table we provide the drive-shaft 78 with a sprocket-wheel 85. A shaft 86 is journaled in a bearing 87 of a bracket 88 secured to the normal table and carries a pinion 89 which meshes with a gear 90 on a shaft 91 journaled in a bearing 92 of the bracket 88, and in a bearing 93 of a bracket 94 secured to the normal table. The shaft 86 is provided with a sprocket-wheel 95, a sprocket-chain 96 taking oversaid sprocket-wheel and the sprocket-wheel 85. A clutch 97 is provided between the adjacent ends of the shafts 91 and 57, a clutch-shifter 98, sliding in bearings 99 of the bracket 94 being adapted to engage or disengage the clutch. The said adjacent ends of the shafts 91 and 57 are preferably separated; the said clutch being also preferably separable for forming a space 100 between said respective clutch-faces and the adjacent ends of said shafts for permitting the band-saw blade to pass the same. The table is also provided with a slit 101 for accommodating the band-saw blade when the latter is placed upon or taken off the wheels, the said slit being substantially coincident

with the space 100. The slit 101 is closely adjacent to the slot or groove 47 for bringing said feed-chain and the band-saw blade into close relation. At said slot or groove the 5 normal table is formed with the slot or groove at one side of said slit and with a rib 103 at the other side of said slit extending lengthwise of said slit for strengthening the normal table at said slit. A link 104 spans the outer end of said slit and is connected to said normal table at both sides of said slit for steadyng the normal table, as by means of bolts 105, 106. The normal table may also be provided with idler-rolls 107. 10 The rear feed-roll bearing may be on an arm 108 having a separable connection 109 with the ram for aiding in ready removal of the band-saw blade.

Having thus fully described our invention 20 what we claim as new and desire to secure by Letters Patent is:

1. A board edging machine comprising the combination of a saw-blade, a normal table over the surface of which the work 25 may be adjusted transversely of the plane of said saw-blade, said table having a slot parallel to the plane of said saw-blade, an endless supplemental table in said slot, and means for permitting relative up and down 30 adjustment between said supplemental table and said normal table adjacent to the cutting range of said saw-blade.

2. A board edging machine comprising the combination of a normal table having a 35 slot substantially parallel to the sides of the saw-blade in said machine, an endless supplemental supporting table in said slot having a board-supporting surface higher than the upper surface of said normal table for supporting the board longitudinally of said board-supporting surface and in raised 40 relation to said normal table, a gage for the work adjustable across the surface of said normal table laterally of the sides of said saw-blade, and means for permitting relative 45 positioning up and down adjacent the cutting range of said saw-blade between said board-supporting surface and the upper surface of said normal table, and constructed 50 and arranged for permitting employment of said machine for edging and for regular sawing purposes, substantially as described.

3. A board edging machine comprising the combination of a normal table having a 55 slot substantially parallel to the sides of the saw-blade in said machine, an endless supplemental supporting table in said slot having a board-supporting surface higher than the upper surface of said normal table for supporting the board longitudinally of said 60 board-supporting surface and in raised relation to said normal table, a gage for the work adjustable across the surface of said normal table laterally of the sides of said saw-blade, 65 means for permitting relative positioning up

and down adjacent the cutting range of said saw-blade between said board-supporting surface and the upper surface of said normal table, and pressure means above said endless supplemental supporting table for pressing the stock upon said endless supplemental supporting table, substantially as described. 70

4. A board edging machine comprising the combination with a normal table having a slot substantially parallel to the sides of the saw-blade in said machine, of an endless supplemental supporting table in said slot having a board-supporting surface higher than the upper surface of said normal table for supporting the board longitudinally of 75 said board-supporting surface and in raised relation to said normal table, a gage for the work adjustable across the surface of said normal table laterally of the sides of said saw-blade, means for permitting relative 80 positioning up and down adjacent the cutting range of said saw-blade between said board-supporting surface and the upper surface of said normal table, and pressure means above said endless supplemental table constituting 85 feeding means for said board, substantially as described.

5. A board edging machine comprising the combination with a normal table having a slot substantially parallel to the sides of the 90 saw-blade in said machine, of an endless supplemental supporting table in said slot having a board-supporting surface higher than the upper surface of said normal table for supporting the board longitudinally of said board-supporting surface and in raised 95 relation to said normal table, a gage for the work adjustable across the surface of said normal table laterally of the sides of said saw-blade, means for permitting relative 100 positioning up and down adjacent the cutting range of said saw-blade between said board-supporting surface and the upper surface of said normal table, a roll above said endless supplemental table, and driving means for 105 actuating said endless supplemental table and roll while feeding a board therebetween, substantially as described.

6. A board edging machine comprising the combination, with the saw-blade, of a 110 normal table, said table having a slot substantially parallel to the sides of the saw-blade in said machine, an endless supplemental traveling board-supporting table in 115 said slot, a wedge for positioning said supplemental table up and down in said slot, adjacent the cutting range of said saw-blade, a gage for the work adjustable across the surface of said normal table laterally of the sides of said saw-blade, the upper face of said 120 wedge and the inner face of said supplemental table having guide-ways between them for guiding said supplemental table longitudinally, substantially as described.

7. A vertical band-saw edging machine 130

comprising the combination with upper and lower band-saw wheels and mandrels therefor, of a normal table having an upper stock surface and a slot therein, an endless supplemental board-supporting table in said slot with an upper feeding surface extending substantially parallel with the axial planes of said saw-wheel mandrels, said normal table having a slit therein adjacent to and extending substantially parallel with said endless supplemental table, driving means for said endless supplemental table, and a separable clutch in said driving means located adjacent to said slit, constructed and arranged for permitting the band-saw blade to be inserted past said clutch and into said slit for the purpose, substantially as described.

8. A board edging machine comprising the combination of a normal table having a slot, an endless supplemental table in said slot having a board - supporting surface higher than the upper surface of said normal table for supporting the board longitudinally of said board - supporting surface and in raised relation to said normal table, means for permitting relative positioning up and down between said board-supporting surface and the upper surface of said normal table, a roll above said endless supplemental table, a roll above said endless supplemental table and roll while feeding a board therebetween, and means for raising said roll, and constructed and arranged for permitting employment of said machine for edging and for regular sawing purposes, substantially as described.

9. A board edging machine comprising the combination of a normal extended flat-top table arranged for ordinary board sawing

purposes, said normal table having a slot, an endless supplemental supporting table in said slot having an upper board-supporting surface, means for permitting relative positioning up and down between said board-supporting surface and the upper surface of said normal table, a roll above said endless supplemental table, and driving means for actuating said endless supplemental table and roll while feeding a board therebetween, and constructed and arranged for permitting employment of said machine for edging and for regular board-sawing purposes, substantially as described.

10. A board edging machine comprising the combination of a normal extended flat-top table arranged for ordinary board sawing purposes, said normal table having a slot, an endless supplemental supporting table in said slot having an upper board-supporting surface higher than the upper surface of said normal table, a roll above said endless supplemental supporting table, driving means for actuating said endless supplemental supporting table and roll while feeding a board therebetween, and adjusting means for said roll, and constructed and arranged for permitting employment of said machine for edging and for regular sawing purposes, substantially as described.

In testimony whereof we have subscribed our names hereto in the presence of two subscribing witnesses.
